UNITED STATES PATENT OFFICE.

THOMAS F. RATAICZAK, OF TROY, OHIO, ASSIGNOR TO THE HOBART MANUFACTURING COMPANY, OF TROY, OHIO, A CORPORATION OF OHIO.

MEAT CHOPPER AND METHOD OF MAKING SAME.

Application filed February 20, 1922. Serial No. 537,777.

To all whom it may concern:

Be it known that I, THOMAS F. RATAICZAK, a citizen of the United States, and a resident of Troy, in the county of Miami and State of Ohio, have invented certain new and useful Improvements in Meat Choppers and Methods of Making Same, of which the following is a full, clear, and exact description, reference being had to the accompanying drawings, forming part of this specification.

My invention relates to the type of meat choppers comprising a casing, a feed worm, a perforated plate and a knife, in which the meat is forced through the perforated plate by the feed screw while the knife, mounted on the stud supporting the outer end of the feed screw revolving with the screw against the inner face of the perforated plate, cuts the meat as it is forced through the perforations.

The supporting stud is screwthreaded unto a threaded socket in the end of the feed screw and is formed with a squared portion to hold the knife. The strains to which the stud is subjected are frequently very severe, resulting in a stripping of the threads on the stud or worm, and at the same time it is extremely desirable to manufacture the squared portion of the stud from material which is extremely tough and hard and which cannot be readily threaded.

It is the object of my invention to provide a cheap and effective method of manufacturing the stud which shall obviate the difficulties above set forth, and it consists of that certain novel construction and arrangement of parts to be hereafter particularly pointed out and claimed.

In the drawings,

Figure 1 is an enlarged side elevation of the stud partly in section.

Figure 2 is central longitudinal section of the meat chopper complete.

The meat chopper as a whole is of an old and well known construction, in which 1 is the casing, with a hopper 2, feed screw 3 and perforated plate 4, with a hub 5 forming a bearing for the stud 6, which is screwed into the threaded socket in the one end of the feed screw, while the other end is secured to the operating shaft 7 journaled in the hub 8 of the casing. The perforated plate 4 is held in place in the end of the

casing by the tightening cap 13 and is locked against rotation by a locking pin 9 inserted through a boss 10 on the casing and engaging a notch 12 in the edge of the perforated plate. The stud 6 is formed with a squared portion 14 upon which is mounted the knife 15.

As stated above, it is desirable to manufacture this portion of the stud out of tough and hard material, so hard as to render it difficult and expensive to cut threads for the attachment to the feed screw. Moreover it is desirable for the square stud to have the maximum torsional strength which can be secured. This latter can best be secured by using a forged or drawn bar of the required size. Furthermore it is very desirable that the strength of the threads on the threaded portion of the stud and its receiving socket shall be as great as possible. This can best be accomplished by making the diameter of the threaded portion as great as possible. I therefore provide the squared inner end of the stud with a comparatively soft metal portion 16. This soft metal portion is formed with a socket to receive the squared end of the stud and is pressed and shrunk in place while the screw threads 17 for attachment to the feed screw are cut on this soft metal portion.

In this way if the knife is subjected to unusual strains while in use there is little danger of the threads in the feed screw being damaged or stripped and should the square stud be damaged the soft metal portion is readily removable from the feed screw to permit of replacement.

Having thus described my invention, what I claim as new and desire to secure by Letters Patent, is:—

1. In a meat chopper, a stud for the feeding and cutting devices, comprising a hard and tough metal portion for the journal bearing and knife mounting parts, and a comparatively soft metal portion for securing the stud to the feeding device.

2. In a meat chopper, a stud for the feeding and cutting devices, comprising a hard and tough metal portion for the journal bearing and knife mounting parts, and a comparatively soft metal portion for securing the stud to the feeding device, the soft metal portion being shrunk around the hard metal portion.

3. In a meat chopper, a stud for the feed-

ing and cutting devices, comprising a hard and tough metal portion for the journal bearing and knife mounting parts, and a comparatively soft metal threaded portion for securing the stud to the feeding device, the soft metal threaded portion being shrunk around the hard metal portion.

4. In a meat chopper, the method of forming studs for the feeding and cutting

devices which consists in forging from hard and tough metal the bearing and squared portions and then in shrinking over the end of the squared portion a comparatively soft metal portion and then cutting screw-threads in the soft metal for securing to the feeding devices.

THOMAS F. RATAICZAK
